(57) **CLAIM**

The ornamental design for a cap for a liquid container, as shown and described herein.

DESCRIPTION

FIG. 1 is a bottom perspective view of the cap for a liquid container showing my new design;

FIG. 2 is a top perspective view thereof;

FIG. 3 is a bottom view thereof;

FIG. 4 is a top view thereof;

FIG. 5 is a side view in direction of arrow 5 of FIG. 4.

FIG. 6 is a side view in direction of arrow 6 of FIG. 4.

FIG. 7 is a side view in direction of arrow 7 of FIG. 4.

FIG. 8 is a side view in direction of arrow 8 of FIG. 4; and, FIG. 9 is a perspective view of the cap in context of a liquid container.

In the drawings, the broken lines show portions of a cap that form no part of the claim; in FIG. 9, the broken lines depict environment that forms no part thereof.
